(57) **CLAIM**

The ornamental design for a food container, as shown and described.

DESCRIPTION

FIG. 1 is a top, rear perspective view of a first embodiment of a food container showing my new design;

FIG. 2 is a top, front perspective view thereof;

FIG. 3 is a right side elevational view thereof;

FIG. 4 is a rear elevational view thereof;

FIG. 5 is a left side elevational view thereof;

FIG. 6 is a front elevational view thereof;

FIG. 7 is a top plan view thereof;

FIG. 8 is a bottom plan view thereof;

FIG. 9 is a top, front perspective view shown with the lid open of FIG. 1 of the food container; and

FIG. 10 is a top, front perspective view shown with the lid partially open of FIG. 1 of the food container.

FIG. 11 is a top, rear perspective view of a second embodiment of a food container showing my new design;

FIG. 12 is a top, front perspective view thereof;

FIG. 13 is a right side elevational view thereof;

FIG. 14 is a rear elevational view thereof;

FIG. 15 is a left side elevational view thereof;

FIG. 16 is a front elevational view thereof;

FIG. 17 is a top plan view thereof;

FIG. 18 is a bottom plan view thereof;

FIG. 19 is a top, front perspective view shown with the lid open of FIG. 11 of the food container; and,

FIG. 20 is a top, front perspective view shown with the lid partially open of FIG. 11 of the food container.

The broken lines in FIGS. 1-16 and 18-20 of the food container are for the purpose of illustrating environmental structure, and form no part of the claimed design.

1 Claim, 12 Drawing Sheets
